1

This invention relates to an improved electrical interrupter.

Interrupters and circuit breakers of many types have been proposed heretofore some of which were in the nature of a fuse which was blown when the safe current value was exceeded and some of which were in the nature of a switching mechanism actuated by a fault, overload or other condition, the former type also including the cartridge type of fuse in which the arc is extinguished by a suitable surrounding liquid or solid medium.

In the beforementioned cartridge type of fuse the interruption of the current is achieved by a fusible element both for the liquid and the solid material arc extinguishing types. This factor limits the use of the cartridge to a specified minimum current so that some faults will not be sufficient to actuate the fuse. The fuse is not usually operated except by melting the fusible element.

It is therefore the principal object of this invention to provide a cartridge type of interrupter with mechanical actuation initiated from any type of fault on the system.

In the previously known forms of fuses or interrupters certain difficulties have existed in breaking the circuit in a safe manner which ensures that the equipment protected by the fuse or interrupter suffers a minimum of damage and it has also been a problem to effectively operate on multi-phase circuits of high operating voltages and currents unless relatively expensive equipment was used.

In order to prevent unbalanced voltages from being impressed on multi-phase consuming apparatus it is desirable with multi-phase systems to interrupt all phases and a further object of this invention is to interrupt all the phases practically simultaneously if a fault or overload occurs on one or more phases.

A still further object of this invention is to provide a relatively simple interrupter which, though it may be used on single-phase installations, it particularly is appropriate for interrupting supply to multi-phase equipment, this object being achieved by interposing the current-interrupting member or members between insulators one at least of which is movable under suitable control to effect the interruption.

In the case of multi-phase circuits the interrupting cartridges in all phases have their action initiated by suitably coupling the movable insulators to effect the desired simultaneous interruption.

2

In accordance with this invention the improved electrical interrupter consists of a plurality of insulators and a support for the insulators to allow relative movement between them. A cartridge which normally carries the current but which may interrupt same is positioned between the insulators and is actuated to interrupt when relative movement occurs between the insulators. A control is provided to initiate the insulator movement.

The cartridge may comprise loaded contacts locked by a withdrawable pin disposed to be displaced when movement occurs between insulators to allow the loaded contacts to part.

Relative movement between the insulators may take a number of forms and may be effected in various ways and while one insulator may be fixed, the other insulator when released may be permitted to fall through a short distance. In the form illustrated the moving insulator is hinged and it is supported by an operating arm, and a trigger release is provided for the operating arm so that an electrically operated trip coil may release the operating arm to give the movement between the insulators.

The cartridges used comprise mechanical current-interrupting means disposed in arc extinguishing means, the current-carrying means of the cartridge being mechanically opened when a force is applied between the ends by relative movement between insulators. Throughout this specification the term "cartridge" is to be given this meaning.

Where the interrupter in accordance with this invention is applied to a multi-phase system each phase has a pair of insulators and the movement between the insulators in each phase is so utilised that it will actuate the cartridges in all phases simultaneously. To give the required simultaneous actuation of a cartridge in each phase, the one insulator may be fixed for each phase and a hinged insulator provided for each phase. The hinged insulators may be coupled together by a shaft which is prevented from turning by an operating arm restrained by a catch which in turn is operated from an electrically operated trip coil which initiates the movement between the insulators in each phase simultaneously.

In order, however, that the invention may be more clearly understood it will now be described with reference to the accompanying drawings in which:

Fig. 1 illustrates a front elevation of a three-phase interrupter in accordance with this in-

vention in which the operating parts for the interrupter on one phase include the insulators and the cartridge but the insulators and cartridges have been removed from the operating sections of the other phases to illustrate the operation of the device.

Fig. 2 is a side elevational section on line 2—2 of Fig. 1 and showing the insulators and cartridge in position upon the operating section of the unit.

Fig. 3 is a section as on line 3—3 of Fig. 1 and illustrates the operating rods for both resetting the mechanism and earthing the line terminals.

Fig. 4 is an enlarged sectional side elevation with the insulators partially broken away illustrating the actuating mechanism for the interrupter.

Fig. 5 is a central sectional elevation illustrating one type of cartridge which may be used in accordance with this invention, and

Fig. 6 is a partial central sectional elevation illustrating a further form of cartridge which may be used in accordance with this invention.

The drawings illustrate a three-phase system incorporating the interrupter but it will be appreciated that the invention may be applied to other multi-phase systems or to a single phase line in a slightly modified form.

The three phases have supports 4, 5 and 6 at the lower end of which are the fixed lower insulators 7 which extend outwardly substantially horizontally with a terminal contact 8 at their outer end to which may be connected the line to be interrupted.

The central support 5 has secured to it a mechanism box 10 having at its forward end bearings for a phase coupling shaft 11 which extends transversely across the supports 4, 5 and 6. The ends of the shaft 11 may turn in bearings upon the supports 4 and 6. Linked with the shaft 11 are the movable insulator supports 12 which each have an upwardly extending arm or bracket 14 the upper end 15 of which is movable along a shaft 16 secured to each of the supports 4, 5 and 6. Each shaft 16 has at its forward end a stop 17 and a spring 18 is positioned between the upper end 15 of the arm 14 and the stop 17. The downward movement of each upper movable insulator 19 which is secured upon the movable insulator support 12 is therefore opposed by the action of the spring 18 which forms buffer means and a limiting device for the downward movement of the insulators 19 when they turn with the phase coupling shaft 11.

The control for the movement between the fixed insulators 7 and the movable insulators 19 for each phase is provided from the insulator release box 10 which is carried upon the central support 5. Carried upon the under side of the mechanism box 10 is a trip coil 20 having a plunger 21 which is arranged to be moved upwardly when the trip coil 20 is energised. A trigger 22 is pivoted at 23 to an operating arm 27 and has a catch 25 adapted to restrain a reset arm 26 pivoted at the rear of the mechanism box 10. The reset arm 26 is positioned above the operating arm 27 which supports the central movable insulator support 12 by means of an adjustable stop 28. The outer pair of movable insulator supports 12 is coupled to the central support 12 by the shaft 11. The trigger 22 is disposed in the path of the plunger 21 and the catch 25 normally holds the reset arm 26 in position and therefore restrains the operating arm 27 which thereby supports the weight of the mov-

able insulators 19 by means of the phase-coupling shaft 11. If a fault or an overload occurs in the system a detecting relay energises the trip coil 20 which will actuate the plunger 21 which will move upwardly and operate the trigger 22 which in turn releases the catch 25 then the reset arm 26 and the operating arm 27 so that the insulators 19 may turn downwardly when the phase-coupling shaft 11 rotates, it being appreciated that the three insulators 19 will move downwardly simultaneously.

In order to reset the catch 25 (as particularly illustrated in Fig. 3) the shaft 30 upon which the reset arm 26 is secured has a lever arm 31 secured to it outside the mechanism box 10 and the free end of the lever arm 31 is coupled to a slotted clevis 32 secured upon the end of a reset rod 34.

To reset the unit after the plunger 21 has returned to its normal position the reset rod 34 is simply moved downwardly which rotates the lever arm 31 and turns the shaft 30 which in turn will move the reset arm 26 downwardly to reset the catch 25 and move the operating arm 27 into its normal position so that the movable insulators 19 will then be lifted upwardly by the shaft 11 in readiness for another tripping operation. The reset rod 34 must be returned to its upper limit in the slotted clevis 32 after the resetting operation.

For each phase the movable insulator 19 has an upper contact 36 incorporating an actuating head 37 and an actuating pin 38. Carried between the actuating head 37 and the lower terminal contact 8 for each phase is the current-interrupting cartridge 39, the cartridges being easily removable for replacement or renewal after the device has been actuated to interrupt the circuit.

The type of current-interrupting cartridge 39 which may be used can be varied according to requirements but the cartridge particularly illustrated in Fig. 5 is of the type having liquid arc extinguishing means and may be actuated from the actuating pin 38 on the actuating head 37.

The lower end of the current interrupting cartridge 39 for each phase is connected to the lower terminal contact 8 by a releasable clamp 40 while the top of the cartridge is connected to the actuating head 37 by means of the releasable clamp 41. The releasable clamp 41 is coupled to the actuating head 37 by means of a clamping extension 42 and the link 43 so that the top of the cartridge 39 is held but will allow downward movement of the insulator 19. The releasable clamp 41 is electrically connected to the upper contact 36 by means of a braided connection.

The actuating pin 38 on the head 37 is normally retained above the surface of the top of the current-interrupting cartridge 39 but when the movable insulator 19 is displaced downwardly when released by the trip coil 20 the actuating pin 38 moves downwardly and strikes a frangible disc 44 positioned in the top of the current-interrupting cartridge 39.

With particular reference to Fig. 5 a liquid type of current-interrupting cartridge is illustrated having an upper cap 45 and a lower cap 46 which are adapted to be carried by the releasable clamps 41 and 40 respectively. Carried between the caps 45 and 46 is the insulating tube 47 of glass. Disposed within the cap 45 of the cartridge is an annular contact 48 which co-operates with a withdrawable contact 49 which is conical in form so that it gives a line contact between it and the annular contact 48. The withdrawable contact

49 is itself spring-loaded to give the required pressure between the contacts to carry the current, the spring 50 being disposed within the tube 47. The conical end of the withdrawable contact 49 is split at 51 and so shaped that this end can collapse inwardly when a holding pin 52 is displaced from same. The angle of the cone is selected to allow the spring 50 to exert the required contacting force and also allow quick withdrawal of the contact 49 from the fixed annular contact 48 when the holding pin 52 is displaced out of its locking position within the split portion of the withdrawable contact 49.

The holding pin 52 has its lower end enlarged in section and is positioned within a reduced diameter section of the withdrawable contact 49 but the other end of the holding pin 52 is adjacent the frangible disc 44. It will be seen that with this arrangement using the frangible disc 44 adjacent the holding pin 52 the cap 45 is sealed at the same time allowing the movement of the pin 52 when the frangible disc 44 is struck by the actuating pin 38.

The tube 47 is filled with a suitable arc-extinguishing fluid and the liquid director 53 is provided adjacent the withdrawable contact and in such a position that when the holding pin 52 is displaced and the contact is interrupted under the influence of the spring 50 a direct flow of arc-extinguishing fluid is directed to the site of the arc. For this purpose the director 53 has a lower conical face arranged to direct a jet of liquid through the annular space between the inner opening of the member 53 and the periphery of the tube which it encircles.

The withdrawable contact 49 is provided with conducting tails 54 to transmit the current from it to the cap 46 at the lower end of the cartridge.

In actual operation when a fault occurs or it is desired to break the circuit the movable insulators 19 for each phase are released from their locked position so that they fall downwardly to allow the actuating pins 39 to strike the frangible disc 44 so that the holding pins 52 are moved downwardly until the reduced section allows the expanded withdrawable contact 49 to collapse and the spring pressure will cause the split portion of the withdrawable contact 49 to be moved inwardly and displaced from its annular contact 48 so that the circuit is automatically broken. At the same time for each phase it will be appreciated that when the circuit is broken and the arc occurs the arc-extinguishing material will automatically be thrown upwardly through the annular gap between the director 53 and the tube which it encircles to extinguish the arc.

One advantage of using this type of cartridge is that it is easily replaceable and it is only necessary to reload the cartridge to provide a new frangible disc 44 and reseal same before the cartridge may be again replaced between the upper and lower releasable clamps 41 and 40 respectively.

Referring now to Fig. 6 a particular type of cartridge is illustrated which could be used in accordance with this invention and could be applied between the insulators in a similar manner to the cartridge illustrated in Fig. 5. The cartridge has a lower cap 56 and an upper cap between which is the fibre tube 57 carrying the solid arc-extinguishing material 58. The lower cap 56 has an annular contact 60 secured to it which co-operates with a withdrawable contact 61 the end of which is specially shaped and is split so that its end can collapse inwardly when a holding pin 62 is

withdrawn from its position in a reduced diameter portion of the withdrawable contact 61. The withdrawable contact 61 is coupled to an upper terminal rod 63 which is spring actuated to displace the withdrawable contact 61 from the annular contact 60. An auxiliary element 64 may be provided in the form of an element or wire which may be blown or broken when the upper terminal rod 63 moves upwardly which initiates the arc-extinguishing means for lower current values while for larger current values the actual breaking of the arc between the annular contact 60 and the withdrawable contact 61 will initiate the vapourising of the arc-extinguishing material 58.

15 It will be seen that the cartridge illustrated in Fig. 6 may be operated in a similar manner to the type illustrated in Fig. 5 and that the holding pin 62 must be actuated by the relative movement between insulators but is normally held at the lower end of the cartridge. Suitable coupling means may be applied from the upper movable insulator 19 to achieve this purpose but it will be appreciated that the lower insulators 7 for each phase could be movable and the upper insulator 19 could be fixed so that the lower terminal contact 8 could provide the movement to remove the holding pin 62 and actuate the cartridge.

In order to provide earthing of the lower terminal contact 8 and the upper contact 36, after 30 the interrupter has operated, earthing blades 66 and 67 are provided for each phase which may be moved on to earthing contacts carried by the contacts 36 and 8 to earth the whole device for removal and replacement of the interrupting cartridge 39.

Although a particular feature of the interrupter is the fact that the control to initiate the insulator movement is in the form of a trip coil, it will be appreciated that the same mechanism could 40 be actuated manually by mechanical tripping of the trigger.

From the foregoing it will be appreciated that an improved electrical interrupter is provided which is characterised by a plurality of insulators 45 at least one of which is movable but is normally held in a fixed position, a self-contained electrical current-carrying cartridge being inserted between the insulators in such a manner that while the insulators are in their locked position the cartridge 50 serves as a current-carrying device but when, because of the operation of a fault detecting relay or other device the one insulator is released to move to a new position such as by falling down under its own weight, means in the cartridge it- 55 self are actuated to break the circuit between the insulators although the cartridge will still remain as a bridge between the insulators, but its capacity to carry current will have been removed because the pin which normally holds the contacts 60 within the cartridge in their current-carrying position will have been actuated to allow the spring means within the cartridge to have drawn the contacts apart and the circuit will thus be broken.

In considering the invention it must be clearly 65 borne in mind that the only insulators used need be the standard types of supporting insulators for switch gear which is being protected, one of which is allowed to move so that the whole of the current-carrying means including the cartridge are 70 fully supported on the two insulators, the movement of the one insulator being only slight as the actual break in the line is effected by a mechanical breaker within the cartridge itself which is merely initiated in its action by the slight movement of the movable insulator.

I am aware that non-movable insulators have prior to this date supported a cartridge in which a break is effected but as the insulators themselves were non-movable it was necessary to carry through one of the insulator's operating means which would have the full operating voltage impressed across it.

I am also aware that insulators have had special breaking means inserted between them which themselves were supported on or by a further movable insulator but in that case an additional insulator was required in which a large movement was necessary so that the gear required was of a relatively complicated nature as compared to my present invention. Also the larger movement necessary to effect the separation of the contacts makes high speed operation impossible.

What I claim is:

1. An improved electrical interrupter characterised by a plurality of insulators, a support for the insulators to allow relative movement between the insulators, means to normally hold the insulators in a fixed position, an electrical current-carrying cartridge between the insulators, axially confined on one insulator, guide means between the other end of the cartridge and the other insulator, a trip coil to initiate the insulator movement, a fixed contact in the cartridge, a withdrawable contact also in the cartridge having its one end split and being spring loaded, a holding pin in the split portion of the withdrawable contact, means on the movable insulator to withdraw the pin when relative movement occurs between insulators, and arc-extinguishing material in the cartridge.

2. An improved electrical interrupter characterised by a fixed insulator and a hinged insulator carried upon a support to allow movement of the hinged insulator, an operating arm to normally support the hinged insulator in a fixed position, a trigger, a catch for the operating arm releasable by the trigger, an electrical current-carrying cartridge between the insulators axially confined on the fixed insulator, guide means between the other end of the cartridge and the hinged insulator, a pin in the cartridge to maintain the circuit, said pin being displaceable by the said hinged insulator, arc-extinguishing means for the cartridge, and an electrically operated trip coil to operate the trigger release.

3. An improved electrical interrupter for multi-phase systems characterised by a fixed and a movable insulator for each phase, a support upon which the fixed insulator for each phase is carried, a transverse phase-coupling shaft to which a movable insulator for each phase is coupled and which shaft may be operated to simultaneously move the insulators, an electrical current-carrying cartridge between the fixed and movable insulators for each phase, means in the cartridge to break the current between the insulators when the shaft is operated, an operating arm coupled to the transverse phase-coupling shaft, a trigger to support the operating arm, a trigger release, and an electrically operated sole-
noid to operate the trigger release.

4. An improved electrical interrupter for a multi-phase system according to claim 3 in which said operating arm is restrained by a reset arm coupled to a lever arm and reset rod, and the reset arm is held by said trigger.

5. An improved electrical interrupter for a multi-phase system characterised by a fixed and a movable insulator for each phase which serve as terminals for current-carrying lines, a support

upon which the fixed insulator for each phase is carried, a transverse phase-coupling shaft to which a movable insulator for each phase is coupled and which shaft may be operated to simultaneously move the insulators, an electrical current-carrying cartridge between the fixed and movable insulators for each phase secured to one insulator and guided by the other, an operating arm secured to the transverse phase-coupling shaft, a trigger to support the operating arm, a catch for the operating arm releasable by the trigger, an electrically operated trip coil to operate the trigger, an actuating pin on the movable insulator for each phase, and said cartridge for each phase comprising a fixed contact and a withdrawable spring loaded contact and a locking pin to normally hold the contacts together, said locking pin being in the path of the said actuating pin to move the locking pin to allow the contacts to disengage under spring action when the movable insulator shaft is rocked.

6. An improved electrical interrupter according to claim 5 in which the withdrawable contact is held in engagement with an annular surface on the fixed contact by the said holding pin which has its one end held in a split portion of the withdrawable contact and its other end in line with the line of movement of the said actuating pin.

7. An improved electrical interrupter for a multi-phase system characterised by a fixed and a movable insulator for each phase which serve as terminals for current-carrying lines, a support upon which the fixed insulator for each phase is carried, a transverse phase-coupling shaft to which a movable insulator for each phase is connected and which shaft may operate to simultaneously move the insulators, an electrical current-carrying cartridge between the fixed and movable insulators for each phase secured to one insulator and guided by the other, an operating arm coupled with the transverse phase-coupling shaft, a trigger, a catch for the operating arm releasable by the trigger, an electrically operated trip coil to operate the trigger, an operating pin on the movable insulator for each phase, said cartridge for each phase comprising a fixed annular contact, a withdrawable contact to fit therein, a holding pin to lock the contacts together, and a spring to urge the contacts apart, said cartridge being in the form of a cylinder having a frangible disc at one end and having the holding pin held in a split portion of the withdrawable contact, the cylinder containing an arc-extinguishing liquid.

8. An improved electrical interrupter for a multi-phase system characterised by a fixed and a movable insulator for each phase, a support upon which the fixed insulator for each phase is carried, a transverse phase-coupling shaft to which a movable insulator for each phase is secured, which shaft may rock in bearings on the support, an electrical current-carrying cartridge between the fixed and movable insulators for each phase secured to one insulator and guided by the other, an operating arm coupled to the transverse phase-coupling shaft, a trigger to support the operating arm, a catch for the operating arm releasable by the trigger, an electrically operating solenoid to operate the trigger, said cartridge for each phase comprising a fixed contact, a withdrawable contact to interrupt the flow of current, a holding pin held in a split portion of the withdrawable contact and actuated by displacement of the movable insulator, and the

cartridge containing a solid arc-extinguishing material.

9. An improved electrical interrupter for a multi-phase system characterised by a fixed insulator for each phase, a transverse phase-coupling shaft carried in bearings on a support, a movable insulator secured to the shaft and extending outwardly for each phase to serve as a terminal for a current-carrying line, a current-carrying cartridge between the fixed and movable insulators for each phase secured to the said fixed insulator and guided by the said movable insulator, releasable contacts in the said cartridge, spring means to urge the said contacts apart, a locking pin to normally hold the said contacts together, an operating connection between the said movable insulator and the said pin, a mechanism box carried by a support for one phase,

10

an operating arm coupled to the shaft and carried in the mechanism box, an electrically operated trip coil carried by the mechanism box, a plunger actuated by the trip coil, a reset arm restraining the operating arm, a catch restraining the reset arm and actuated by the plunger to release the weight of the movable insulator, and spring loading to control the striking force of the movable insulator for each phase.
